UNITED STATES PATENT OFFICE.

JOSEPH KENNEDY, OF NEW YORK, N. Y., ASSIGNOR TO THE CLEMENTS COMPANY, A CORPORATION OF NEW YORK.

EXPANSION-ANCHOR.

1,100,661.

Specification of Letters Patent. Patented June 16, 1914.

Application filed July 20, 1912. Serial No. 710,589.

To all whom it may concern:

Be it known that I, JOSEPH KENNEDY, a citizen of the United States, and a resident of the city, county, and State of New York, have invented certain new and useful Improvements in Expansion-Anchors, of which the following is a specification, reference being had to the accompanying drawings, forming a part thereof.

10 My invention relates to improvements in expansion anchors of the character employed for obtaining anchorage in brick or stone walls or the like, of which the material is of a character not adapted to directly receive 15 and hold a threaded bolt.

A feature of the present invention contemplates in addition to the provision of a longitudinally segmental anchor having its outer surface corrugated or ribbed for a portion 20 of its length which makes it better adapted to engage the sides of the hole in the wall when forced apart by its expander, the construction of the anchor which provides for the bolt which is used with it acting 25 upon an expander and also engaging the inner end of the anchor itself in the manner which is illustrated in the accompanying drawings which I describe in the following specification and the novel features of which 30 I will set forth in appended claims.

Referring to the drawings:—Figure 1 is a side elevation of an anchor constructed in accordance with my invention together with a bolt. Fig. 2 is a transverse vertical section 35 of the same parts taken on the line 2—2 of Fig. 1 and drawn on a somewhat larger scale. Fig. 3 is a central longitudinal elevation of the bolt and anchor with the anchor and its expander shown in section, the 40 view being taken at right angles to that shown in Fig. 1. Fig. 4 is a transverse vertical section on an enlarged scale taken on the line 4—4 of Fig. 3. Fig. 5 is a central longitudinal section showing the anchor expanded. Fig. 6 is a side elevation on an enlarged scale of a conical expanding member 45 or nut.

Like characters of reference designate corresponding parts in all of the figures.

50 The anchor comprises a shell divided longitudinally throughout its length into two

parts 10 and 11. This shell has a longitudinal bore of which the forward portion 12 is cylindrical and smooth and but slightly greater than the diameter of the bolt which 55 is to be used therewith. At the inner end of this cylindrical part of the bore is a portion 14 which may be conical with its sides diverging from the end of the cylindrical portion toward the inner or rear end of the 60 anchor. The anchor or larger end of this conical portion 14 is joined with a shallow beveled recess 15 formed in the inner end wall 16 of the anchor. Through the end of this end wall a hole 17 is provided which is 65 somewhat smaller than the diameter of the bolt.

At the line of joinder of the two parts of the shell the inner portion of it is provided with a pair of substantially diamond shaped 70 recesses 19. These recesses are adapted to receive correspondingly shaped ears or lugs 20 which project laterally from the periphery of a nut 21 which in this case is conical and is adapted to be held within the conical bore 14. This nut and its lugs 20 are of such size and shape that they allow the two parts 10 and 11 of the shell to lie together before expansion. The sides of the lugs 20 are undercut as shown at 22. This is for the 80 purpose of preventing the sides of the shell at recesses 19 being pushed out over the lugs by lateral bending. In fact this construction gives the metal of the shell a tendency to grip the lugs of the expander more tightly 85 and to prevent loss of expansion due to the spreading of the sides of the shell. This feature is set forth and claimed in my co-pending application Serial No. 696,675 filed May 11, 1912, and is not an essential part of 90 my present invention. The nut 21 is threaded to receive a bolt 23.

In use a hole is drilled in the wall or other structure of sufficient size to permit the insertion of the anchor. The bolt is then 95 screwed into the nut 21 and through it until it engages the rigid inner end wall 16 of the shell. A further rotation of the bolt forces the nut forward and as the lugs 20 prevent the expanding nut from turning their 100 wedge-like or tapered form causes the desired expansion to be effected. When the

nut itself is of conical exterior form and lies in a similarly formed pocket, it too pushes the two parts of the shell apart. The shell is thus forced apart until the hole 17 is 5 made large enough to allow the bolt to pass through it. This then effectively prevents the inner ends of the two parts of the shell bending in toward each other, thereby providing a holding bearing at the rear end of 10 the shell and establishing a bearing against the surfaces of the hole in the wall throughout the length of the shell. As soon as the nut has advanced a sufficient amount to obtain a holding effect of the shell upon the 15 wall, the bolt may be advanced through the nut to tighten any object which may be between the head of the bolt and the surface of the wall, against such surface without the necessity of having any thrust bearing upon 20 the outer end of the shell. If such parts become loose, a further turning of the bolt will produce a further expansion to obtain a new hold upon the surface of the hole and to again tighten the object.

25 If desired the end walls may be made beveled as shown so that the pressure of the end of the bolt against them also tends to force the two parts of the shell apart. The corrugations on the outside of the shell present a rough surface which aids in preventing the withdrawal of the anchor from the wall especially when the device is used in comparatively soft material such as brick or concrete.

30 35^a What I claim is:

1. A bolt anchor comprising a tubular shell split longitudinally, an internally threaded longitudinally movable expander within said shell, and rigid members integral with the parts of said shell forming a transverse bearing surface, said members being constructed to form a central opening smaller than the bolt which is to be used with said anchor, the sides of said opening 40 forming bearing surfaces for the bolt after the parts of the shell are expanded.

2. A bolt anchor comprising a tubular shell split longitudinally, an internally threaded longitudinally movable expander within said shell, means for preventing rotation of said expander relative to the shell, and rigid members integral with the parts of the shell forming a transverse bearing surface across the inner end of the shell, said members being constructed to form a central opening smaller than the bolt which is to be used within said anchor, the sides of said opening forming bearing surfaces for the bolt after the parts of the shell are expanded.

3. A bolt anchor comprising a tubular shell split longitudinally, said shell being constructed with a pocket, rigid bearing members integral with the parts of said shell forming a bearing surface across the

inner end of the shell near the end of said pocket, said members being constructed to form a central opening smaller than the bolt which is to be used with said anchor, the sides of said opening forming bearing surfaces for the bolt after the parts of the shell are expanded; an internally threaded expander in said pocket, and wedge-shaped lugs projecting transversely from opposite sides of the expander through the sides of the shell.

4. A bolt anchor comprising a tubular shell split longitudinally, said shell being constructed with a conical pocket flaring toward the inner end of the shell, rigid members integral with the parts of said shell forming a bearing surface across the inner end of the shell near the end of said pocket, said members being constructed to form a central opening smaller than the bolt which is to be used with said anchor, the sides of said opening forming bearing surfaces for the bolt after the parts of the shell are expanded; an internally threaded expander in said pocket and wedge-shaped lugs projecting transversely from opposite sides of the expander through the sides of the shell.

5. A bolt anchor comprising a tubular shell split longitudinally, said shell being constructed with a pocket, and a pair of opposed apertures from said pocket through the sides of the shell at the division lines thereof, said apertures having converging walls, rigid members integral with the parts of said shell forming a bearing surface across the inner end of the shell near the end of said pocket, said members being constructed to form a central opening smaller than the bolt which is to be used with said anchor, the sides of said opening forming bearing surfaces for the bolt after the parts of the shell are expanded; an internally threaded expander in said pocket, and a pair of wedge-shaped lugs forming bearing surfaces projecting transversely from opposite sides of the expander into said apertures.

6. The combination with a bolt anchor comprising a tubular shell split longitudinally, said shell being constructed with a conical pocket flaring toward the inner end of the shell, and a pair of opposed substantially diamond-shaped apertures from said pocket through the shell at the division lines thereof, rigid integral members projecting inwardly to form a beveled bearing surface across the inner end of the shell, said members being constructed to form a central opening smaller than the bolt which is to be used with said anchor, the sides of said opening forming bearing surfaces for the bolt after the parts of the shell are expanded; an internally threaded expanding member of conical exterior within said pocket having diamond-shaped lugs forming bearing surfaces entering said apertures and

adapted to pass through the opening in said wall when the anchor is expanded, and corrugations on the outer periphery of the shell; of a bolt having the threaded portion thereof passing through and fitted into the threaded portion of the expander and projecting beyond the expander into contact with the said rigid members and having

a portion protruding beyond the outer end of the shell.

In witness whereof, I have hereunto set my hand this 19th day of July 1912.

JOSEPH KENNEDY.
